5 Claims. (Cl. 200—31)

This invention relates to a device for sensing changes in the pressure of a liquid at one point, for example, underground, and signaling deviations in such pressure at a remote point, for example, above ground.

The general object is to provide a new and improved device of the above character which is especially adapted for use in sensing changes in water pressure in a pitless water pump installation and actuating the pump control switch in a location that may be subject to freezing temperatures.

Other objects and advantages of the invention will become apparent from the following detailed description taken in connection with the accompanying drawings in which:

FIGURE 1 is a fragmentary elevational view of a pitless pump construction equipped with a pressure sensing device embodying the novel features of the present invention.

FIG. 2 is a fragmentary vertical central sectional view.

FIG. 3 is a fragmentary perspective view of the fitting for supporting the pressure switch.

FIG. 4 is a fragmentary section taken along the line 4—4 of FIG. 2.

FIG. 5 is a fragmentary longitudinal section of a modified type of mounting for the pressure sensing and switch actuator.

For purposes of illustration, the invention is shown in the drawings incorporated in a pitless pump installation of the reciprocating deep well type including aligned tubes 10 and 11 threaded into a hollow casting 12 disposed underground and below the normal frost line. An outlet 13 from the casting communicates through a pipe 9 with a storage tank (not shown) which is located at some distance from the pump installation.

The upper tube 11 projects above the ground level and is closed by a two-part cap 14 bolted to a ring 59 which is threaded onto the tube 11. The ring supports the power actuator 15 for the pump, the actuator including, in this instance, an electric motor 16 adapted to be started and stopped in response to closure and opening of a switch 17. The latter is disposed in a weatherproof enclosure preferably mounted in a readily accessible position above ground and exteriorly of the well casing. In the deep well pump shown for purposes of illustration, the pump includes a piston 18 reciprocable in a cylinder 19 disposed below the frost line and defined by the lower end portion of a tube 20 within the casing and extending upwardly through the cap 14. The rod 21 of the piston is coupled to a crank driven through a suitable speed reducer by the motor 16.

The lower end of the tube 20 threads into the upper end of the hollow core 22 of a spool 23 having upper and lower flanges 24 and 25, respectively, cooperating with the internal wall of the casting 12 to define an annular water passage 26 communicating with the discharge outlet 13. This passage is closed by suitable seals such as O rings 27 seated in peripheral grooves around the spool flanges and pressed against cylindrical surfaces within the casting 12 above and below the discharge outlet. At its lower end, the spool core supports and communicates with a pipe 28 projecting downwardly through the casing 10 to a point below the water level in the well.

A second piston 18a (FIG. 1) is disposed in the lower

2

end of the pipe 28, which constitutes a cylinder 19a for the piston, and the latter is connected to the piston 18 by a vertical rod 21a so that the two pistons reciprocate together. As disclosed more fully in Patent No. 2,657,633, the piston 18a carries an automatic valve which opens on the downstroke and closes on the upstroke. Beneath the piston 18a is a foot valve 22a which also is automatic and closes on the downstroke while opening on the upstroke.

During the upstroke of the reciprocating parts of the pump, a portion of the water forced upwardly through the pipe 28 by the piston 18a occupies the space vacated by the piston 18 and the remainder of the water is forced through an opening 29 in the core 22 into the passage 26 and the outlet pipe 9. This opening is controlled by a valve 30 preferably of the flapper type shown in Patent No. 2,657,633 and comprising a disk 31 bodily movable toward and away from a seat 32 and continuously urged toward the latter by a spring (not shown). On the downstroke the foot valve 22a closes causing delivery of the water displaced by the piston 18 through the check valve 30 and the outlet pipe 9.

In accordance with the present invention, novel means is provided for sensing pressure changes within the passage 26 or the pipe 9 and therefore within the water storage tank and transmitting such changes to an actuator 33 for the switch 17 by which the pump motor is started and stopped. In the form shown in FIG. 2, the transmitting means is disposed within and extends along the narrow space 32a between the tube 20 of the pump and the inner wall of the well casing. This transmitting means includes a conduit 34, 51 communicating with the passage 26 and extending up through the space 32a and out through the casing 11 or the cap 14 to the switch actuator 33. A flexible partition 38 disposed beneath the frost line divides this conduit into upper and lower sections or chambers 60, 61, respectively, the lower section 61 being subjected to the pressure in the passage 26 while the upper section 60 contains a non-freezing liquid 50. In this way, the pressure in the passage 26 is transmitted to the switch actuator 33 through the flexible partition 38 and the liquid 50.

In the present instance, the sensing means includes a rigid walled pipe 34 lying alongside the cylinder 19 and supported as through a threaded nipple 35 on the upper flange 24 of the spool 23 from which the pipe projects upwardly. Herein, the nipple threads into the lower end of the pipe and a hole 36 extending upwardly through the flange 24 for establishing communication between the passage 26 and the interior of the pipe. A coupling 37 threaded into the upper end of the tube 34 tightly closes the latter and has a lower end portion of reduced diameter closely telescoping with and cemented to a flexible wall partition which is closed at its lower end by a plug 39 and thereby constitutes the partition 38. Preferably, the partition 38, which is made of a flexible plastic material, is of somewhat smaller normal diameter than the pipe 34 and extends substantially throughout the full length of the pipe 34 which is disposed below the frost line.

The invention also contemplates preventing momentary pressure surges in the water passage and storage tank from being transmitted to the pressure switch and producing false actuation thereof. This is accomplished by interposing in the lower chamber 61 within the tube 34 an orifice 62 which is small enough in area to prevent a substantial flow of water therethrough during the relatively short interval that the pressure surges persist as in the case of a reciprocating type of pump. As shown in FIG. 4, a bore is in one end of the nipple. In a pumping system operating between 20 p.s.i. and 40 p.s.i., an orifice having a diameter of .042 of an inch will

effectively prevent the switch 17 from responding to normal surges in the water pressure.

Herein, the switch actuator 33 includes a flexible diaphragm 40 forming one wall of a chamber 41 having a rigid wall 42 threaded onto the outer end 43^a of a hollow fitting 43. The latter projects through the cap 14 and is clamped rigidly to the cap by a nut 44 screwed onto threads 44^a on the fitting (FIG. 3). Such clamping without turning of the fitting is facilitated by coaction between a non-circular head 45 on the fitting with the flat faces of lugs 47 on the inner wall of the cap. A gasket disposed between the head 45 and the lower cap 14^a (FIG. 3) forms a water-tight seal around the fitting 43.

Through a plunger 46, the diaphragm motion is transmitted to a lever 48 which, through suitable over-center means, opens and closes the switch 17 with a snap action. By adjusting the stress of a spring 49, the pressures in the chamber 41 at which the switch is opened and closed may be varied as desired.

A capillary tube 51 is permanently joined as by soldering to the coupling 37 and to the fitting 43 so as to connect the interior of the flexible partition 38 through the bore or passage of the coupling with a passage 45^a extending through the fitting. To transmit the pressure changes in the water tank to the switch actuator 33, the tube 38, the capillary tube and the passage 45^a are filled with the anti-freeze solution 50 or other liquid which will not solidify at freezing temperatures and is nontoxic. To facilitate bending during assembly of the cap 14 on the well casing, the tube 51 is looped or coiled intermediate its ends as indicated at 52.

It will be apparent that the pipe 34, the partition 38, the capillary 51 and the fitting 43 constitute a self-contained unit in which the solution 50 may be retained by a suitable cap (not shown) covering the outer end of the fitting. Before the spool and pump assembly is lowered into the well casing, the tube 34 is coupled to the spool by screwing the nipple 35 into the hole 36. When the spool reaches its final position against shoulders 53 on the casting 12, the fitting 43 will, due to the extra length of the capillary 51, project above the upper end of the casing 11. As the lower part 14^a of the cap 14 is fitted down onto a gasket 54 on the ring 59, the outer shank portion of the fitting 43 is threaded through a hole 55 and the head 45 fitted in against the lug 47. Then the nut 44 is screwed onto the shank of the fitting which is held against turning, thus avoiding any possibility of twisting the capillary tube or breaking the joint between the latter and the fitting. The upper part 14^b of the cap is fitted over the upper end of the tube 26 and clamped down against the sealing gland 56 by tightening nuts 57 on tie bolts 58 projecting upwardly from the ring 59.

Finally, the cap on the fitting 43 is removed and the switch housing is screwed onto the outer end of the fitting. This establishes communication between the flexible tube 38 and the chamber 41 of the switch actuator. Then, when the pump is started, the water pressure built up in the passage 26 will contract the tube 38 forcing fluid through the capillary tube into the chamber 41. By properly adjusting the spring 49, the switch 17 may be adapted to respond to any desired range of pressure within the water storage tank.

In operation, it will be apparent that the partition 38 will expand and contract with changes in the water pressure within the storage tank, the passage 26 and the pipe 34 thus causing the solution 50 to flow back and forth through the capillary tube 51 thereby transmitting the pressure changes to the diaphragm 40. As a result, the switch 17 will be opened and closed as the water pressure rises above and falls below a range predetermined by the adjustment of the switch. The viscosity of the liquid flowing back and forth in the capillary tube 51 and the restriction of the orifice 62 resists the transmission of rapid changes in pressure and thus prevents opening and

closing of the switch due to momentary pressure variation in the passage 26.

With the arrangement described above, the partition 38, the coupling 37, the capillary tube 51 and the fitting 43 may be assembled with the pipe 34 and filled with fluid 50, capped, and shipped as a unit. This permits the use of factory made joints which practically eliminate the possibility of the liquid 50 leaking. Any such leaking might result in a permanent reduction of pressure in the chamber 41 so that the switch 17 would remain closed and the pump operate continuously regardless of the pressure in the passage 26.

If desired, pressure changes in the storage tank may be sensed at a point in the water passage outside of the well casing and in the delivery pipe 9. Such a modification is shown in FIG. 5 in which the parts in common with FIG. 2 bear corresponding reference numerals. While the nipple 35 may be threaded directly into a T-shaped fitting interposed in the pipe, it is in the present instance coupled to the top of a small dome-shaped casting 64 having threaded flanges 65 into which adjacent ends of the pipe 9 are screwed.

With this arrangement, a substantial volume of air may accumulate in the dome and acts as the medium for transmitting the pressure changes to the lower chamber 61 and therefore to the flexible partition 38. As before, the damage of false actuation of the switch is minimized by interposing a restriction 62 in the passage through the nipple 35.

The conduit 34 and the capillary tube 51 are enclosed in a tube 69 screwed at its lower end into the top of the dome 64 and at its upper end into a cap 66 supporting the stem 43 of the switch actuator 33. With the housing 65 thus mounted and disposed outside of the well casing, the pressure sensing parts may be removed easily for servicing. After removal of switch casing 33 and the cap 66, the conduit may be unscrewed and detached from the dome 64 by means of a suitable tool engaged with lugs 67 around the upper end of the conduit. Replacement of the conduit in the dome 64 is facilitated by tapering the lower end of the nipple 35 to form a conical surface 68 by which the nipple is guided into the hole into the dome to bring the nipple threads into engagement with those in the dome.

The pressure sensing and transmitting means in the forms described above is simple and inexpensive in construction and compactly arranged within the narrow space available in the well casing. It may be installed without twisting or other deformation of the coupled parts which might break the joints and result in objectionable leakage.

This application is a continuation-in-part of my co-pending application, Serial No. 691,438, filed October 24, 1957, and now abandoned.

55 I claim as my invention:

1. In a device for sensing changes in water pressure in a pitless water pump installation of the deep well type and actuating the pump control switch of said installation, the combination of a well enclosure having a water passage therein, said water passage being located below the frost line, a pressure actuating switch located above said water passage and outside of said well enclosure where it is subjected to freezing temperatures, said switch including an actuator chamber, a fluid tight conduit for transmitting pressure changes from said water passage to the actuator chamber of said pressure actuated switch, said conduit comprising a rigid walled tube connected at one end in fluid tight communication with said water passage, a tubular coupling closing the other end of said tube and having a passage extending therethrough, a capillary tube having one end permanently sealed in said coupling in communication with said passage in said tubular coupling, a tubular fitting extending from the inside to the outside of said well enclosure and mounted 60 in the wall of the enclosure, said fitting having a passage

extending therethrough, the other end of said capillary tube being permanently sealed to the inner end of said fitting in communication with the passage therethrough, the outside end of said fitting forming the terminal of said conduit, a mechanically detachable fluid tight connection joining the outer end of said fitting and the actuator chamber of said pressure actuated switch with said actuator chamber in communication with said fitting passage, a flexible tube closed at one end and loosely fitting within said rigid walled tube with the other end 10 permanently sealed to the inner end of said coupling and communicating with the passage therein, said flexible tube forming a pressure transmitting fluid tight partition separating said conduit into upper and lower sections, and a non-freezing liquid substantially filling said upper section.

2. In a device for sensing changes in water pressure in a pitless water pump installation of the deep well type and actuating the pump control switch of said installation, the combination of a well enclosure having a water passage therein, said water passage being located below the frost line, a pressure actuated switch located above said water passage and outside said well enclosure where it is subjected to freezing temperatures, said switch including an actuator chamber, a fluid tight conduit for transmitting pressure changes from said water passage to the actuator chamber of said pressure actuated switch, said conduit comprising a rigid walled tube connected at one end in fluid tight communication with said water passage, a capillary tube permanently sealed to the other end of said tube and communicating therewith, a tubular fitting extending from the inside to the outside of said enclosure and mounted in the wall of said well enclosure, said fitting having a passage therethrough and the other end of said capillary tube being permanently sealed to the inner end of said fitting in communication with said fitting passage, means providing a fluid tight connection between the outer end of the fitting and said actuator chamber of said pressure actuated switch, a flexible wall within said tube permanently sealed to the wall of said conduit to form a pressure transmitting fluid tight partition in said conduit, and a non-freezing liquid substantially filling said conduit above said partition.

3. In a device for sensing changes in water pressure in a pitless water pump installation of the deep well type and actuating the pump control switch of said installation, the combination of a well enclosure having a water passage therein, said water passage being located below the frost line, a pressure actuated switch located above said water passage and outside of said well enclosure where it is subjected to freezing temperatures, said switch including an actuator chamber, a fluid tight conduit for transmitting pressure changes from said water passage to the actuator chamber of said pressure actuated switch, said conduit comprising a rigid walled tube connected at one end in fluid tight communication with said water passage, a tubular coupling closing the other end of said tube and having a passage extending therethrough, a capillary tube having one end permanently sealed in said coupling in communication with said passage in said tubular coupling, a tubular fitting extending from the inside to the outside of said well enclosure and mounted in the wall of the enclosure, said fitting having a passage extending therethrough, the other end of said capillary tube being permanently sealed to the inner end of said fitting in communication with the passage therethrough, the outside end of said fitting forming the terminal of said conduit, a mechanically detachable fluid tight connection joining the outer end of said fitting and the actuator chamber of said pressure actuated switch with said actuator chamber in communication with said fitting passage, a flexible tube closed at one end and loosely fitting within said rigid walled tube with the outer end permanently sealed to the inner end of said coupling and communicating with the passage therein, said

5 flexible tube forming a pressure transmitting fluid tight partition separating said conduit into upper and lower sections, said fluid tight conduit and said flexible tube constituting a unitary assembly having a detachable threaded connection with a defining wall of said water passage, and a non-freezing liquid substantially filling said upper section.

4. In a device for sensing changes in water pressure in a pitless water pump installation of the deep well type and actuating the pump control switch of said installation, the combination of a well enclosure having a water passage therein, said water passage being located below the frost line, a pressure actuated switch located above said water passage and outside of said well enclosure where it is subjected to freezing temperatures, said switch including an actuator chamber, a fluid tight conduit for transmitting pressure changes from said water passage to the actuator chamber of said pressure actuated switch, said conduit comprising a rigid walled tube connected at one end in fluid tight communication with said water passage, a tubular coupling closing the other end of said tube and having a passage extending therethrough, a capillary tube having one end permanently sealed in said coupling in communication with said passage in said tubular coupling, a tubular fitting extending from the inside to the outside of said well enclosure and mounted in the wall of the enclosure, said fitting having a passage extending therethrough, the other end of said capillary tube being permanently sealed to the inner end of said fitting in communication with the passage therethrough, the outside end of said fitting forming the terminal of said conduit, a mechanically detachable fluid tight connection joining the outer end of said fitting and the actuator chamber of said pressure actuated switch with said actuator chamber in communication with said fitting passage, a flexible tube closed at one end and loosely fitting within said rigid walled tube with the outer end permanently sealed to the inner end of said coupling and communicating with the passage therein, said flexible tube forming a pressure transmitting fluid tight partition separating said conduit into upper and lower sections, said lower section including a restricted passage between said water passage and said lower section sufficiently small in area to prevent the transmission of momentary pressure pulses in said water passage through said restricted passage to said upper section and actuation of said pressure actuated switch in response to such pulses, and a non-freezing liquid substantially filling said upper section.

50 5. A device for sensing changes in pressure of water flowing in a passage, the combination of an enclosure defining a water passage, a pump for forcing water through said passage, a pressure actuated switch having an actuating chamber for controlling operation of said pump, said water passage being located below the frost line and said switch being located above said frost line, a tubular enclosure extending upwardly from a wall defining said water passage, a fluid tight conduit within said tubular enclosure for transmitting pressure changes from said water passage to the actuator chamber of said pressure actuated switch and comprising a unitary assembly including a rigid walled tube within said tubular enclosure, means for detachably connecting one end of said rigid walled tube to a defining wall of said water passage, a capillary tube within said tubular enclosure having one end permanently sealed to the other end of said rigid walled tube and communicating therewith, a tubular fitting extending from the inside to the outside of said tubular enclosure and mounted in a wall of said tubular enclosure, said fitting having a passage therethrough communicating with the actuator chamber of said switch, and the other end of said capillary tube being permanently sealed to the inner end of said tubular fitting in communication with said fitting passage, a flexible tube loosely fitting within said rigid walled tube

and closed at one end with its other end permanently sealed to said other end of said capillary tube and in communication therewith, said flexible tube forming a pressure transmitting fluid tight partition separating said fluid tight conduit into upper and lower sections, and a non-freezing liquid substantially filling said upper section, said unitary assembly including said rigid walled tube, the means for detachably connecting said rigid walled tube to a wall defining said water passage, the capillary tube, the tubular fitting, and said flexible tube being removable as a unit from said tubular enclosure upon detaching said connecting means between said rigid walled tube and the wall defining said water passage.
